UNITED STATES PATENT OFFICE.

ALONZO LINTON BAUSMAN, OF CHICOPEE, MASSACHUSETTS, ASSIGNOR TO NATIONAL EQUIPMENT COMPANY, OF SPRINGFIELD, MASSACHUSETTS, A CORPORATION OF MASSACHUSETTS.

REDUCING AND REFINING APPARATUS.

1,337,583.

Specification of Letters Patent. Patented Apr. 20, 1920.

Application filed March 8, 1919. Serial No. 281,515.

To all whom it may concern:

Be it known that I, ALONZO LINTON BAUSMAN, a citizen of the United States of America, residing at Chicopee, in the county of Hampden and State of Massachusetts, have invented certain new and useful Improvements in Reducing and Refining Apparatus, of which the following is a specification.

10 My invention relates to an improved reducing and refining apparatus which is more particularly adapted for the treatment of cocoa nibs and the production therefrom of finished and refined chocolate liquor. The 15 machine is characterized in that the material may be treated continuously and uninterruptedly through all the steps from the reduction of the nibs to the production of the refined liquor.

20 As is well understood in the art, the cocoa nibs are first reduced to produce a coarse or unrefined chocolate liquor, and, then, this liquor is refined to produce the finished chocolate liquor. The apparatus of my invention, not only combines in a single machine a reducing apparatus and a refining apparatus, but also includes provisions, whereby the coarse and unrefined liquor is conducted directly and continuously from 30 the reducer to the refiner, such provisions embodying mechanism for treating such liquor to place it in proper condition to be handled and treated by the refiner. Thus, I provide an apparatus, whereby cocoa nibs 35 can be continuously and uninterruptedly treated to produce finished and refined chocolate liquor, at speeds, and with a convenience and surety of a superior product, heretofore unattainable.

40 One object of my invention is to provide an apparatus for the continuous and uninterrupted production of refined chocolate liquor from cocoa nibs.

Another object is to provide an apparatus 45 combining a reducer, a refiner, and connecting provisions therebetween for so treating the unrefined liquor from the reducer as to prepare it for subsequent treatment by the refiner.

50 To these ends, and also to improve generally upon devices of the character indicated, my invention consists in the following matters hereinafter described and claimed.

Without restricting my invention thereto, 55 I describe it in connection with the appa-

ratus illustrated in the accompanying drawings, and embodying it. In these drawings:

Figure 1 is a side elevational view of the apparatus; 60

Fig. 1^a is a fragmentary elevational view supplemental to Fig. 1;

Fig. 2 is a sectional elevational view of the hopper for the reducer, and its feeding mechanism; 65

Fig. 3 is a fragmentary end view of the machine illustrative of the delivery trough and adjacent parts;

Fig. 4 is an end view of the pump actuating mechanism for the refiner, being substantially a reproduction of Fig. 2 of U. S. Patent No. 1,035,304, Bausman, Aug. 13, 1912, grinding mill; and 70

Fig. 5 is a somewhat conventional plan view of certain parts of the refiner, being 75 substantially a reproduction of Fig. 9 of the above-mentioned patent, and having the parts moved all into one plane for purposes of diagrammatic illustration.

The illustrated apparatus (Fig. 1) comprises the reducer B, the refiner C, and the liquor conducting and treating provisions D. The reducer B will be described more fully hereinafter, but it will suffice for the present to say that, broadly, it is of the usual type having (Fig. 2) two stationary reducing disks 14 and 15, and an intermediate rotating reducing disk 13 for co-operation with the stationary disks 14 and 15. These disks are designed and contoured for the primary purpose of reducing the cocoa nibs to produce a coarse or unrefined chocolate liquor and it is not practical or feasible to produce finished and refined liquor, with a single type of disk. As a result, and as 85 is now standard practice in the art, this reducer produces a coarse chocolate liquor in which the cocoa butter and the fibrous elements of the cocoa beans are not thoroughly combined and compounded into a 90 smooth and uniformly mixed liquor capable of being properly fed into a standard commercial refiner C of the type illustrated in the above-mentioned patent.

This refiner needs, for the present, no 105 specific description. Suffice it to note that it comprises a disk e which revolves between two stationary disks f and g, the reducing surfaces of the disks being suitably contoured to refine the chocolate liquor. The 110

refiner also includes a pump (the parts *u*, *t*, *v*, 32, 33) for feeding exact measured quantities of unrefined liquor to each side of the rotating wheel. Now, it is to be noted that, 5 from the nature of the case, the reducing surfaces of this refiner are not well adapted for working on the coarse liquor as discharged from the reducer. And, it is to be further noted, that a measuring pump, particularly one of the piston type (which type has been found best, and is a standard commercial part of the aforesaid refiner) will not handle well the coarse liquor discharged from the reducer.

15 As pointed out above, one of the principal objects of my invention is the combining of a reducer and a refiner, of the character just above indicated, into a single apparatus in which the two machines will co-act to produce refined chocolate liquor from 20 cocoa nibs, continuously and uninterruptedly. I produce the combination by combining with the two machines a third mechanism—the liquor conducting and preparing 25 provisions *D*. This mechanism takes the discharge from the reducer and, while transmitting it to the refiner, prepares it for handling by the refiner. Thus, the complete combination gives an apparatus which 30 continuously and uninterruptedly treats the material from the cocoa nib stage to, and through, the refined chocolate liquor stage.

This mechanism *D* comprises a cylindrical shell 1, which is supported at one end 35 by the reducer and, at the other, by the refiner and which is connected at one end to the discharge hopper 2 of the reducer (Fig. 3), to receive the discharge therefrom and at the other end to the inlet 32 of the refiner feed pump. Rotatably mounted in the shell 1, and extending from end to end thereof, is a combined means for conveying 40 and treating the coarse liquor, such means being exemplified by the screw 3. This element 3 is a feeding element of such character as to readily receive and convey the coarse liquor discharged from the hopper 2, which liquor by reason of its thick heavy 45 and stringlike nature does not readily flow, particularly to the degree necessary for it to pass, or be drawn into, the passages *v* and past the valves *u* of the refiner pump. This thick, heavy liquor will, however, readily pass into the casing 1 and be conveyed 50 therein by the element 3. Now it is a known fact in the art that thick, coarse liquor of the character mentioned may be softened and rendered of greater fluidity by subjecting it to a churning action. This, I believe 55 to be due primarily to a thorough amalgamation or compounding of the fibrous elements of the cocoa bean with the cocoa butter constituents thereof. According to this invention the type of liquor conveying element employed is so chosen as to be capable 60

of exerting a churning action on the liquor, as by the screw element 3. Thus, the one element 3 serves the double purpose of conveying the coarse liquor and of so treating it during its conveyance that it can be readily handled by the refiner pump as soon as it reaches the latter.

Preferably, as a valuable adjunct to the churning action of element 3 in softening the liquor and rendering it of greater fluidity, a heating jacket 4 is provided, which jacket encompasses a substantial portion of the casing 1, as indicated in Fig. 1. Conveniently, the element 3 is rotated by gear 5 fixed to the shaft 6 thereof and the gear 5 meshes with a gear 7 fixed to a suitably supported shaft 8. The latter is, in turn, driven by a chain 9 and suitable sprockets from a shaft 10, which is driven by a gear 11 fixed thereon. This gear 11 and its shaft 10 are 85 the driving means for the reducer *B*, which, therefore, will next be described.

The shaft 10 described is rotatably mounted in a pedestal 12 and extends therethrough and projects therebeyond to carry the rotating circular reducing disk 13. At each side of the disk 13 are stationary circular reducing disks 14, suitably supported by the pedestal 12. As here shown, one disk 14 is directly carried by the pedestal and the other 95 is adjustably supported by bolts 16 upon the pedestal and is pressed toward the other disks by springs 17. Each disk 14 has an aperture 17 therein, through which the charge is fed to the space between it and the central disk 13, the charge being delivered from a hopper 18 all as shown in Fig. 2.

Each hopper 18 includes, among its provisions, a loosening and agitating mechanism and associated with both is a mechanism for continuously and automatically delivering substantially equal quantities of material into each. The latter mechanism will be first described. A measuring hopper 19 is carried by arms 20, one at each side thereof, which arms are mounted for oscillation about the axis 21, so that the hopper 19 will discharge first to one and then to the other hopper 18. Below the outlet of the hopper 19 is an arcuate shield 22 curved about the axis 21 as a center and extending from front to back of the hopper 19, and bridging the gap between the hoppers 18. At each end this shield is provided with an upstanding wall 23. The outlet portion of the hopper 19 lies between these walls 23, and the side walls of such portion are apertured, as at 24, to present a passage for the material. Adjustable gates 25 are provided for the apertures 24. The hopper 19 is oscillated by a rod 26 which pivotally connects the arm 20 to the crank pin 28 of an oscillatable crank 29 (Fig. 1). (In the drawings this rod 26 lies behind 130

another rod 44 to be later described.) The crank 29 is pivoted to the frame at 30 (Fig. 1) and receives motion from a link 31 which connects it to one arm 34 of a bell crank lever, the other arm 35 of which is connected by a ball joint 37 to one end of a link 36 which extends and is suitably connected to a crank pin 38 fixed eccentrically on the face of a gear 39 driven by a gear 40, fixed on the described shaft 10.

The loosening and agitating mechanism of the hopper comprises the reciprocable push rods 41, one for each hopper 18 and means for actuating them. As to this actuating means:—the pivot pin 30 of the crank 29 is fixedly connected with the latter to be oscillated thereby, and carries thereon a crank 42 (Fig. 2). This crank 42 is connected by a pin and slot connection 43 to the upper end of the left-hand (Fig. 2) rod 41, to reciprocate the same. For reciprocating the other rod 41, the pin 28, which, as before described, is carried by the crank 29 and has the rod 26 pivotally connected thereto, 25 has also a rod 44 pivotally connected thereto. This rod 44 extends across the hoppers 18 and has its other end connected to a crank 45 (Fig. 1^a) fixedly connected to a shaft 46 oscillatably mounted upon the hopper wall. This shaft 46 has fixed thereto a crank 47 which is connected by a pin and slot connection 48 with the other rod 41. So, both rods 41, and the hopper 19, are actuated from the gear 40 on the shaft 10.

It is in the driving of the gear 11, and in the mounting of the shaft 10, that the merely structural aspects of the "hook up" between the refiner and the reducer appear. The upright *c* of the refiner *C* of the aforementioned Patent No. 1,035,304 is modified slightly in form, as compared with the showing in said patent, and increased in height to provide a bearing for the shaft 10. And the driving shaft *k* of the refiner is extended to the right (Fig. 1) beyond the pedestal *c* to carry, fast thereon, the gear 49, the latter being in mesh with the gear 11 to drive the same.

It now remains to describe the refiner *C*, and its more important features will be described, but only briefly, for reference is made to the above-mentioned Patent 1,035,304 for a full disclosure thereof and description of detailed matters with which the present invention has no concern. I refer to the present drawings and to said patent, by the reference characters used in said patent, and used in the present drawings to designate like parts:—

The refiner comprises the central rotatable reducing disk *e* flanked at each side by a co-operating stationary reducing member *f* or *g*. Liquor is fed in measured quantities through the pipe *z* to the member *g*, and through the pipe *y* to the member *f*. These

quantities are measured out by the pump elements *u*, *v*, *t*, 32, 33, which include the measuring piston 33 and a slide valve so actuated with relation to the piston that, while liquor is being drawn in behind the piston from the distribution chamber 32, a measured quantity is being discharged through the slide valve to one of the pipes *y* or *z*. The valve and pump operating mechanism is shown in some detail in Fig. 4, but since it is like that described in the aforesaid patent, and shown in Fig. 2 thereof, it is believed not to require specific description here. Suffice it to say that the rotating disk *e* and the pump are driven from the pulley *i*, by way of the main driving shaft *h*, a pinion on the shaft *h* in mesh with the gear *h*, the shaft *A*, the eccentric *m* and the cam *n*, the shaft *A* being supported in the uprights *b* and *d* and the shaft *h* being supported in the uprights *d* and *c*, all as more fully described in the patent.

The operation of the apparatus will sufficiently appear from the foregoing description. It is, however, particularly to be noted that the refiner of the type described is characterized in that equal measured charges are supplied to both coacting pairs of reducing disks. The reducer, according to this invention, has likewise been so arranged that to each coacting pair of reducing disks, measured and substantially equal charges are supplied. Furthermore, the measuring hopper 19 is preferably so arranged as to supply to the reducer a supply of nibs substantially equivalent to the charge of liquor supplied to the refiner, and the feeding elements of one operate in substantial synchronism with the feeding elements of the other.

Thus, I have provided an apparatus, which is so constructed and assembled that cocoa nibs or the like can be fed to the reducer and converted into the usual coarse and unrefined liquor, such liquor treated to make it suitable for introduction into the commercial refiner, and then refined, in a continuous uninterrupted operation.

It is recognized that modification may be made in the one embodiment of the invention herein disclosed for illustrative purposes and it is therefore desired to have the scope of the invention defined by the appended claims, interpreted by the spirit of the present disclosure rather than by the letter of the exact form disclosed.

What I claim is—

1. The combination with apparatus for reducing cocoa nibs or the like to the condition of a coarse liquor, of an apparatus for refining such liquor and including a measuring feed pump by which the liquor is forced to the refiner, and a combined churning and conveying means to which the coarse liquor from the reducing apparatus is automatically supplied and by which such liquor is

automatically mixed and rendered sufficiently fluid to enter said pump.

2. The combination with apparatus for reducing cocoa nibs or the like to the condition of a coarse liquor, of an apparatus for refining such liquor and including a measuring feed pump by which the liquor is forced to the refiner, and a combined churning and conveying means to which the coarse liquor from the reducing apparatus is automatically supplied and by which such liquor is automatically mixed and rendered sufficiently fluid to enter said pump, and means to heat the liquor during its passage through said means.

3. In an apparatus of the character indicated, in combination, a reducer, a refiner, and means located operatively between said refiner and said reducer to receive the discharge from said reducer, churn it preparatory to its introduction to said refiner, and transmit it thereto.

4. In an apparatus of the character indicated, in combination, a refiner including means for measuring and delivering determined quantities of chocolate liquor thereto, a reducer including means for measuring and delivering determined quantities of cocoa nibs or the like thereto, means for conducting the discharge from said reducer to the measuring and delivering means of said refiner, and means for operating the measuring and delivering means of said refiner and the measuring and delivering means of said reducer in substantial synchronism, thereby to deliver in a given time a quantity of cocoa nibs to the reducer substantially equivalent to the liquor supplied by the delivering and measuring means to the refiner.

5. In an apparatus of the character indicated, in combination, a refiner including a main driving shaft, a driven refining element, a driven measuring device, and driv-

ing connections between said shaft and said element and said device, a reducer including a driven reducing element and driving connections for said element, a driven member located operatively between said refiner and said reducer to receive the discharge from the reducer, prepare it, and deliver it to the measuring device of said refiner, and driving connections between said main driving shaft and the driving connections of said reducer, and between said shaft and said member, whereby said various driven parts are all driven from said main driving shaft of said refiner.

6. In an apparatus of the character indicated, in combination, a refiner presenting a driven refining element and a driven measuring device, a driving shaft operatively connected with said element and device to drive the same and carrying a gear, a reducer presenting a driven reducing element and a driving shaft operatively connected with said element to drive the same and carrying a gear, a driven member arranged operatively between the refiner and reducer to receive the discharge from the latter, prepare it, and deliver it to the measuring device of the refiner, driving connections between said member and the driving shaft of the reducer, and a main driving shaft carrying gears, one to engage with the gear of the refiner and the other to engage with the gear of said reducer.

7. In an apparatus of the character indicated, in combination, a refiner presenting a driven refining element, a reducer presenting a driven reducing element, a driven member located operatively between the refiner and reducer to receive the discharge from the latter, churn it, and deliver it to said refiner, and a common means for driving said refiner, reducer, and member.

ALONZO LINTON BAUSMAN.
